No. 36,423.

Patented July 14, 1903.

UNITED STATES PATENT OFFICE.

WILLIAM H. SAART, OF ATTLEBORO, MASSACHUSETTS, ASSIGNOR TO
THE BRISTOL MANUFACTURING COMPANY, A CORPORATION OF
RHODE ISLAND.

DESIGN FOR A HANDLE FOR NAIL-CLEANERS OR SIMILAR ARTICLES.

SPECIFICATION forming part of Design No. 36,423, dated July 14, 1903.

Application filed June 12, 1903. Serial No. 161,244. Term of patent 3½ years.

To all whom it may concern:

Be it known that I, WILLIAM H. SAART, a citizen of the United States, residing at Attleboro, in the county of Attleboro and State of Massachusetts, have invented a certain new, original, and ornamental Design for the Handle of a Nail-Cleaner or Similar Article, of which the following is a specification, reference being had therein to the accompanying drawings.

Figure 1 is the obverse, which is identical with the reverse, of a manicure-handle em-

bodying my design; and Fig. 2 an edge view of the same.

What I claim as new, and desire to secure by Letters Patent, is—

The ornamental design for the handle of a nail-cleaner or similar article, as shown.

In testimony whereof I have affixed my signature in presence of two witnesses.

WILLIAM H. SAART.
